UNITED STATES PATENT OFFICE.

ELMER METIVIER, OF BOSTON, MASSACHUSETTS.

TOOTH-BRUSH.

Specification of Letters Patent. Patented Apr. 27, 1915.

1,137,651.

Application filed July 7, 1914. Serial No. 849,536.

To all whom it may concern:

Be it known that I, ELMER METIVIER, a citizen of the United States, residing at Boston, in the county of Suffolk and State of Massachusetts, have invented new and useful 5 Improvements in Tooth-Brushes, of which the following is a specification.

An object of the invention is to provide a tooth brush of a simple construction and 10 which can be kept in a clean and sanitary condition.

The invention contemplates, among other features, the provision of a tooth brush which will be convenient for traveling in 15 that it can be arranged to take up very little room, while at the same time it will be kept in a clean condition and prevented from contact with other things or from being contaminated with germs or dust.

20 In the further disclosure of the invention reference is to be had to the accompanying drawings, constituting a part of this specification, in which similar characters of reference denote corresponding parts in all the 25 views, and in which:

Figure 1 is a perspective view of the tooth brush, showing the same in position for use; Fig. 2 is a side elevation of the brush when not in use, the cap being shown in dotted 30 lines; Fig. 3 is a vertical transverse sectional view taken through the brush body and the protector or cover shown in Fig. 2; Fig. 4 is a side elevation of a modified form of brush with the cap shown in dotted lines; 35 Fig. 5 is a side elevation of a modified form of brush somewhat similar to the construction shown in Fig. 1, but showing the brush entirely inclosed in the cap and holder, the latter being shown in section; and Fig. 6 is a side elevation of another modified form of 40 brush, with the cap shown in section.

Referring more particularly to Figs. 1, 2 and 3, I provide a handle 10 at one end of which is arranged a brush body 11 consisting of the usual bristles, the brush body 45 being secured to the handle in any convenient manner. Mounted to swing on the other end of the handle 10 is an auxiliary handle 12. The handle 10 has a threaded portion 13 and, similarly, the auxiliary handle 12 has a threaded portion 14.

The free end of the auxiliary handle 12 is enlarged and grooved to form a protector or cover 15 for the brush body 11. Now it 55 will be apparent that when the brush is in use the auxiliary handle 12 is swung away

from the handle 10 as shown, so as to uncover the brush body 11, whereas when the brush is not in use the auxiliary handle 12 is swung to extend longitudinally to the 60 handle 10, adjacent thereto, so that the brush body 11 will lie in the grooved protector or cover 15 whereby the brush body will be kept in a clean and sanitary condition. It will be particularly noted that when 65 the auxiliary handle is in closed position, or as stated, in position to protect the brush body 11, the threaded portions 13 and 14 will form an annular band around the handle and auxiliary handle, with the threads of 70 each portion registering with those of the other so that a member 16, in the nature of a cap and having a threaded end, can be arranged to inclose the handles 10 and 12, the threaded end of the member or cap 16 75 connecting and threading on to the threaded portions 13 and 14.

In Fig. 4 I disclose a modified form of brush and in which the auxiliary handle 12 does not carry a protector or cover such as 80 indicated in Fig. 1 by the numeral 15, but has its free end provided with a threaded portion 17 similar to the threaded portion 14 and which threaded portion 17 is adapted to register or aline with the threaded 85 portion 13 of the handle 10 so that the cap or member 16, when arranged in position to have its threaded end engage the threaded portions 13 and 17, will constitute the covering or protector for the brush body 11, it 90 being seen that in this construction the protector or cover 15, shown in Fig. 1, is dispensed with.

In Fig. 5 I disclose another modified form of brush and in which the handle 10, brush 95 body 11, auxiliary handle 12 and protector or covering 15 are the same as indicated and shown in Fig. 1, the only difference here being that the entire device, including and formed by the handle, auxiliary handle, 100 brush body and protector, is inclosed in a holder 18 to which is threaded the cap or member 16, so that the entire article will be inclosed and protected.

In Fig. 6 I disclose still another modified 105 form of brush and in which instance the handle, auxiliary handle, brush body and protector or covering are indicated by the same numerals as in Figs. 1 and 5. In this instance, however, the handle 10 is provided 110 with an integral knob or bead 19 and a cap 20, similar to the cap or member 16, but not

threaded, is adapted to inclose the brush body and protector or covering with the inner surface of the cap frictionally engaging the knob 19 and a slightly bulged portion 21 of the auxiliary handle so as to hold the cap in engagement with the brush.

From the foregoing description it will be apparent that the brushes described are substantially similar in principle, the only difference being that they vary slightly in the manner of protecting the same to keep the brush body in a clean and sanitary condition. It will be understood that the caps employed in the various structures disclosed can each be provided with a suitable clasp 22 whereby the brush can be held in a pocket similar to the manner of holding a fountain pen in the pocket, and it will be clearly seen that the primary object of providing a tooth brush of a simple construction and which can be conveniently carried in the pocket or in a suit-case when traveling, is accomplished with the various structures disclosed, the brush body in each instance being kept in a clean and sanitary condition when not in use and particularly when moist, after being used, being prevented from coming in contact with other things or the clothing, while at the same time the brush body will be so constructed that it will not be subject to dust, dirt or germs.

Having thus described my invention, I claim:

1. In a brush, the combination with a main handle, of a brush body thereon, an auxiliary handle mounted to swing on the main handle, a cap, and means on the main handle and auxiliary handle and adapted

to be engaged by the cap to hold the same in locked relation to the said main and auxiliary handles and hold the said handles in locked relation. 40

2. In a brush, the combination with a handle, of a brush body thereon, an auxiliary handle, and means for association with the said main handle and auxiliary handle for holding the same in relatively locked position, said means forming a covering for the said brush body. 45

3. In a brush, the combination with a brush body, of a handle carrying the brush body, an auxiliary handle on the first mentioned handle, a threaded portion on the first mentioned handle, a threaded portion on the auxiliary handle and adapted to be 55 alined with the threaded portion of the first mentioned handle, and a cap for threaded engagement with the threaded portions of the said handles. 50

4. In combination with a brush handle, a second handle mounted to swing on the first mentioned handle, a cap, and relatively co-operating means on each of the handles for holding the cap in locked relation thereto. 60

5. A brush comprising a plurality of handles relatively connected to fold upon one another, a brush body on one of said handles, and means encircling said handles and forming a covering for said brush body. 65

In testimony whereof I affix my signature 70 in presence of two witnesses.

ELMER METIVIER.
